Primary Examiner — David G Muller(74) *Attorney, Agent, or Firm* — Nathan S. Smith; Morgan, Lewis & Bockius LLP(57) **CLAIM**

The ornamental design for a syringe device, as shown and described.

DESCRIPTION

FIG. 1 is a front, top perspective view of a syringe device; FIG. 2 is a right side view of the syringe device of FIG. 1; FIG. 3 is a left side view of the syringe device of FIG. 1; FIG. 4 is a top plan view of the syringe device of FIG. 1; FIG. 5 is a bottom plan view of the syringe device of FIG. 1;

FIG. 6 is a rear side view of the syringe device of FIG. 1; and,

FIG. 7 is a front side view of the syringe device of FIG. 1. The broken lines shown in the figures are included for the purpose of illustration and form no part of the claimed design.
